Specification of Letters Patent.

Patented June 8, 1915.

Application filed November 29, 1913. Serial No. 803,724.

To all whom it may concern:

Be it known that I, WILLIAM E. SPARKS, a citizen of the United States, residing in the city and county of New Haven and State 5 of Connecticut, have invented certain new and useful Improvements in Locks, of which the following is a full, clear, and exact description.

This invention relates to locks, and more 10 particularly, to corridor door locks of hotels.

The invention has special reference to a hotel lock, having a latch bolt, a single dead bolt protractable from either side of the door (the dead bolt being operable from the 15 outside by a cylinder lock mechanism having the usual series of keys), and means for dogging or blocking the outside knob, or other latch manipulating device, automatically when the dead bolt is thrown from the 20 inside of the room without dogging it when the door is locked from the outside. Nevertheless, certain features of the invention are applicable to locks of other types.

The primary objects of the invention are 25 to provide improved means in connection with the cylinder lock mechanism for operating the dead bolt by means of a special key or keys, more especially with a view to the simplification of the cylinder lock mechanism employed in locks of the type indicated; to furnish a cylinder lock mechanism, including a bit or dog carried at the rear end of the key plug or barrel, and adapted to be extended rearwardly from the cylinder 30 lock by the use of one key, without being so extended when another key or keys are used; to provide improved and simplified tumbler mechanism for the dead bolt; to provide improved and simplified means for dogging 35 the knob mechanism, under the conditions above stated; and to improve the general construction and operation of devices of the class to which my invention relates.

To these and other ends, the invention 40 consists in the novel features and combinations of parts to be hereinafter described and claimed.

In the accompanying drawings, Figure 1 45 is an elevation of a lock embodying my improvements, with the cap plate removed, the

dead bolt being in its retracted position; Fig. 2 is a similar view, showing the position of the parts when the dead bolt has been protracted from the inside of the door; Fig. 3 is a reverse view of the upper portion 55 of Fig. 1; Fig. 3^a is a section on line 3^a—3^a of Fig. 3; Fig. 4 is a reverse view of the upper portion of Fig. 2; Fig. 5 is a view similar to Fig. 4, showing the dead bolt partly retracted from the exterior of the 60 room, by means of the emergency key; Fig. 6 is a view similar to Fig. 1, showing the position of the parts when the bolt is thrown from the exterior by the change or guest key; Fig. 7 is a section on line 7—7 of Fig. 65 3, showing the guest key in the cylinder lock; Fig. 8 is a section on line 8—8 of Fig. 5; Fig. 9 is a section on line 9—9 of Fig. 8; Fig. 10 is a detail view of the upper portion 70 of the lock, with the dead bolt removed; Fig. 11 is a section on line 11—11 of Fig. 1; Fig. 12 is a section on line 12—12 of Fig. 1; Fig. 13 is a section on line 13—13 of Fig. 2; and Fig. 14 is a detail of the master key and 75 the display key.

Referring to the drawings, the lock case 20 is shown as equipped with the usual latch bolt 21, adapted for operation by the ordinary hub 22 and knob shoe or yoke 23. The hub 22 is adapted for actuation by the customary knob spindle (not shown). The case 20 also contains a sliding member 24, preferably formed as a dead bolt projecting through the face of the case, and adapted for protraction and retraction either by a 80 cylinder lock mechanism 25, at the outside of the door, or by a thumb-turn hub 26, or its equivalent, adapted for operation from the inside.

The bolt 24 is provided at its upper portion, in proximity with the cylinder lock mechanism 25, with talons 27, between which operates a projection 28 of a tumbler 29. This tumbler is pivoted on the bolt at 30, and is provided with a stump 31, adapted to 90 co-operate in the usual manner with a fence or racking post 32 on the cap plate. Under certain conditions, the bolt can be thrown and retracted by a bit or dog 33 of the cylinder lock mechanism 25. The bit or dog 33 95 100

is arranged and operated in the manner described in Letters Patent Number 1,069,734, granted to Sargent & Company, on August 12, 1913, as assignee of John H. Shaw. The 5 bit or rollback 33 may be operated by the guest key 34 (Fig. 7), master key 35 (Fig. 14), display key 36 (Fig. 14), and emergency key 37 (Fig. 8). It is adapted to enter between the talons 27 and engage said 10 talons, and the projection 28 of the tumbler in the usual manner, to protract and retract the dead bolt.

The tumbler 29 may be termed the primary tumbler of the dead bolt. Another 15 tumbler 38 adapted for operation by the thumb-turn hub 26 may be termed the secondary tumbler, and said secondary tumbler is adapted to act on the primary tumbler in such a manner that the thumb-turn hub will 20 operate said tumblers together. The tumbler 38 is of the special shape illustrated in Fig. 8. It consists of a plate adapted to slide on the back of the lock case, behind the dead bolt 24, and provided with an arm 39 for coöperation with the cylinder lock mechanism 25. It is also provided with an arm 40, having a pin 41, with which the thumb-turn hub 26 coöperates in the usual manner. The tumbler 38 is guided in a direction generally parallel to the bolt by means of a slot 42, taking over a post 43 on the case, and it is provided with shoulders 44, 45 respectively, to coöperate with a racking post or fence 46 on the back of the case. A 30 spring 47 acts on this tumbler in such a manner that when said tumbler occupies the position shown in dotted lines in Fig. 10, the tumbler will be deadlocked by engagement of the shoulder 44 with the rear face of the post 46, whereas when said tumbler occupies the position shown in full lines in Fig. 10, it will be deadlocked by engagement of the shoulder 45 with the front face of the post. The primary tumbler 29 is 40 adapted to be operated by the secondary tumbler in the following way: A lug 48, extending backward from the tumbler 29 (Fig. 3^a), operates in a slot 49 of the tumbler 38 (Figs. 4 and 5), which slot is provided at its rear end (relatively to the face of the lock) with a notch forming a shoulder 50, with which the lug 48 is engaged, when the parts are in the positions shown in Figs. 1 and 4. The spring 29^a of tumbler 29 50 normally holds said tumbler interlocked with the tumbler 38 by engaging the lug 48 with the notch just mentioned, but the lug may be disengaged from the notch by the bit or dog 33 of the cylinder lock, whereupon 60 the tumbler 29 and bolt 24 may be moved forward independently of the tumbler 38, with the lug 48 sliding freely in the slot 49. The upper arm 39 of the tumbler 38 lies in close proximity to the cylinder lock mecha-

nism 25, and said arm is adapted to be engaged by a supplemental bit or dog 51, associated with the cylinder lock mechanism. The bit or rollback 51 instead of being mounted on the wall of the case, as in some prior locks, is carried wholly by the cylinder lock and permanently attached thereto. It is rigidly fixed to a member 53, such as a slide, adapted to be projected rearwardly out of the rear end of the keyway, by engagement with the rear end of the emergency key 37, as shown in Fig. 8. In this position, the bit 51 will lie in the plane of the arm 39 of the secondary tumbler, so that the latter may be operated by rotation of the emergency key. A spring 54, acting 80 on the slide 53, within the key plug or barrel normally holds the bit 51 in retracted position, wherein it is in close proximity to the bit 33, and located out of the plane of the secondary tumbler. The ends of the guest key 34 and master key 35 are so shaped relatively to the slide 53 that they will not project the same, and the bit 51, but the end of the display key 36 is shaped like that of the emergency key 37, so that the display 90 key will also move said bit into coöperation with the secondary tumbler.

At its lower portion, the secondary tumbler 38 is provided with a projection 55 coöperating with the recessed end 56 of an elbow lever 57 pivoted in the case at 58 in proximity to the knob shoe 23. In order to provide clearance for the lever 57, the knob shoe is cut away at 59, and an edge 60 of the cut away portion 59 presents a shoulder on the knob shoe to coöperate with a shoulder 61 on the lower extremity of the lever. In the position shown in Fig. 1, the lever 57 is so located as to permit free movement of the knob shoe, whereby the knobs may be freely operated to retract the latch bolt. When, however, the secondary tumbler 38 is thrown forward relatively to the face plate of the lock, as shown in Fig. 2, the projection 55 will rock the lever 57 on its pivot to such an extent that the shoulder 61 of said lever will move into position back of the shoulder 60 of the knob shoe. In this manner, the secondary tumbler will actuate the lever 57 to dog the knob shoe, whereby the rotation of 110 the knobs will be prevented.

The operation of the lock is substantially as follows: When the guest desires to lock his room against intrusion, he throws the 120 dead bolt 24 by manipulation of the usual inside thumb-turn (not shown) connected with the thumb-turn hub 26. In this operation, the thumb-turn hub acts on the arm 40 of the secondary tumbler and depresses the latter, so as to disengage the racking post or 125 fence 46. At the same time, the upper arm 39 of the secondary tumbler, having the slot 49, depresses the primary tumbler 29 by en-

gagement with the upper surface of the lug 48, whereby the stump 31 of the tumbler 29 is disengaged from the racking post or fence 32. With both tumblers released in this manner, the continued rotation of the thumb-turn will protract said tumblers and the bolt in an obvious manner, the lug 48 of the primary tumbler remaining in engagement with the shoulder 50 of the secondary tumbler. Moreover, in addition to operating the bolt, the secondary tumbler dogs the knob shoe in the manner previously described (Fig. 2), and the dogging of the outside knob will indicate to anyone at the outside of the door that the room is occupied. Ordinarily, the chamber-maid on finding the outside knob locked against movement will not attempt to open the door by means of her key, *i. e.*, master key 35, but, in any event, the said master key 35 will be inoperative to retract the dead bolt. This follows from the inability of the bit 33 (the only bit of the cylinder lock operated by the master key) to act on the secondary tumbler 38, which is deadlocked by engagement of its shoulder 45 with the post 46, as previously explained, and in turn deadlocks the dead bolt by engagement of a projection 38^a, with a shoulder 38^b, on the bolt shank. The emergency, or proprietor's key 37, will, however, be operative to withdraw the bolt, under the conditions noted, so that the proprietor may have access to the room at all times. This follows from the fact that said key when inserted in the cylinder lock 25, will move the supplemental bit 51 into the plane of the tumbler 38, as previously described. Then upon rotation of said key, the primary and secondary tumblers will be operated conjointly in an obvious manner by means of the bits 33 and 51 respectively. The bit 33 will move the stump 31 out of engagement with the fence 32, and the bit 51 will disengage the tumbler 38 from the fence 46, so that the engagement of the bit 33, with the talons 27, will then retract the bolt. As the secondary tumbler is moved back from the face of the case, the dogging lever 57 will be actuated in an obvious manner to release the knob shoe.

When the parts are in the position shown in Fig. 1, the guest key 34, or master key 35, may be used to operate the dead bolt and its primary tumbler independently of the secondary tumbler. The bit 33 of the cylinder lock will depress the tumbler 29 independently of the tumbler 38, and will coöperate with the talons 27 in the usual manner, the lug 48 of tumbler 29 being moved to the forward end of the slot 49. Inasmuch as the secondary tumbler is unaffected by this operation, the dogging lever 57 will remain in a position to permit the free operation of the knobs, as shown in

Figs. 6 and 12. This will indicate that the room is unoccupied.

The purpose of the display key 36 is well understood in the art, and its operation need not be referred to in detail, except to say that it and the emergency key will throw the bolt by actuation of both primary and secondary tumblers, thereby serving as shut-out keys relatively to the guest and master keys. Manifestly, the different keys used in connection with the lock may be varied in number as desired, except that it is necessary to have at least one key which will operate only one bit of the cylinder lock mechanism, and another key which will operate both bits.

The foregoing description is necessarily a detailed one, in so far as it concerns the particular embodiment of my invention selected for illustration and description, and I have not attempted to illustrate and describe the numerous modifications which may be adopted within the scope of the claims.

I do not claim herein the cylinder lock *per se*, as the same forms the subject matter of my divisional application, Serial No. 846,802 filed June 23, 1914.

What I claim is:

1. In a lock, a sliding member, a plurality of tumblers therefor, a cylinder lock, a bit carried by said cylinder lock to engage one of said tumblers, and another bit eccentric to the first carried by said cylinder lock to engage another tumbler; substantially as described.

2. In a lock, a case, two members in said case, a cylinder lock mechanism associated with said case, two bits or rollbacks for said cylinder lock mechanism adapted to operate the respective members aforesaid, and a plurality of keys for said cylinder lock mechanism, one of said bits or rollbacks being displaceable relative to the other and relative to one of said members by one of said keys; substantially as described.

3. In a lock, a case, two movable members therein, a cylinder lock mechanism associated with said case, a rollback for said cylinder lock mechanism fixed in coöperation with one of said members, and a second rollback for said cylinder lock mechanism movable relative to the first rollback and to the other member by means of a certain key; substantially as described.

4. In a lock, a case, a cylinder lock secured in an opening in said case, separate members in said case adapted for operation by said cylinder lock, said members having operating abutments or surfaces lying in different planes, and separate bits or rollbacks carried by said cylinder lock and rotatable by certain keys, one of said rollbacks being permanently rotatable into en-

gagement with one of said members, and the other rollback being normally rotatable out of engagement with the other member but projectable into engagement with such 5 other member by means of a certain key; substantially as described.

5. In a lock, a case, a cylinder lock secured in an opening in said case, separate members in said case adapted for operation 10 by said cylinder lock, said members lying in different planes, and separate bits carried by said cylinder lock, one of said bits normally lying in the plane of one of said members, and the other bit normally lying 15 out of the plane of the other member, but projectable into such plane; substantially as described.

6. The combination with lock mechanism of a pin tumbler lock having a key plug, 20 said key plug provided with a keyway, a rollback for operating said lock mechanism, connected with the rear end of the key plug, a second rollback, a plurality of keys insertible into said keyway, and a member 25 carrying said second rollback, movable relative to said first rollback by one of said keys and adapted to actuate said lock mechanism by means of said second rollback; substantially as described.

30 7. The combination, with lock mechanism, of a pin tumbler lock having a key plug, said key plug provided with a keyway, a rollback connected with the rear end of said key plug and adapted to operate a part of 35 said lock mechanism, a second rollback, a plurality of keys insertible into said keyway, and a member carrying said second rollback and projecting into the keyway and movable relative to the first rollback by 40 engagement with one of said keys, said member being adapted when so moved to operate another part of said lock mechanism by said second rollback and being inoperative by another of said keys; substantially as described.

45 8. In a lock, a casing, a bolt controlling mechanism mounted therein, a second bolt controlling mechanism within said casing in a different plane from said first controlling mechanism, a cylinder lock mechanism carried by said casing having an operating member operatively positioned relative to one of said mechanisms and operable by a series of keys to operate said mechanism and having also a second operating member 50 bodily movable relative to the first operating member and normally inoperatively positioned relative to the other of said bolt controlling mechanisms, and means to so position said second operating member relative to said other bolt controlling mechanism by a certain key whereby it may actuate said mechanism.

60 9. In a lock, a casing, a primary mecha-

nism therein provided with an operating 65 abutment, a secondary mechanism having an operating abutment positioned in a different plane from said primary abutment, a rotatable element provided with an operating member normally positioned to rotate 70 with said element in an arc in the plane of one of said abutments, a second operating member movable relative to said first operating member and positioned to rotate with 75 said member in an arc normally out of the plane of the other of said abutments, tumbler mechanism coöperating with said rotatable element, a series of keys coöperating with said rotatable element and tumbler mechanism to rotate said element and operating members to engage one of said abutments and operate its mechanism through said fixed operating member, said relatively movable operating member being adapted for operation and being positioned by one certain of said series of keys to rotate with said element in an arc in the plane of the other of said abutments and to engage the same and operate its mechanism 80 upon the rotation of said element.

90 10. In a lock, a casing, a dead-bolt therein, a cylinder lock mechanism carried by said casing and having a relatively fixed bolt-actuating member, and a second and relatively movable actuating-member positioned in a different plane from said fixed member, said fixed member being operable from one side of the door by a series of keys to project and retract said bolt, manually controlled mechanism operable from the opposite side of the door to project and retract said bolt and operable also to project and lock said bolt against retraction from the opposite side through said series of keys, and another and certain key coöperating with said cylinder lock from said opposite side of the door to bodily move said second bolt-actuating member relative to said fixed member and to a position to coöperate with 95 said manually controlled mechanism to re- 100 tract and project said dead-bolt.

110 11. In a lock, a casing, a dead-bolt therein, primary and secondary tumbler mechanism positioned in different planes and co-operating with said bolt, a cylinder lock mechanism carried by said casing and embodying a key controlled rotatable plug, a relatively fixed rollback operatively connected to said plug, and a second rollback movable relative to the first rollback, said 115 rollbacks being positioned in different planes and said fixed rollback being operable by a series of keys from one side of the door to engage said primary tumbler mechanism and bolt to project and retract said bolt, means normally positioning said movable rollback to rotate with said plug and first rollback in an arc out of the planes of 120 125

5 said tumbler mechanisms, manually controlled mechanism operable from the side opposite said cylinder lock to operate said primary and secondary tumbler mechanism and to project and retract said bolt, said secondary tumbler mechanism being constructed and arranged when actuated to project said bolt, to lock said bolt against retraction from the opposite side through said 10 series of keys, and means operable from said opposite side through a certain key whereby said movable rollback is positioned to rotate with said plug and first rollback in an arc in the plane of said secondary tumbler 15 mechanism to engage said mechanism to project and retract said bolt independently of said manually controlled means.

12. The combination with lock mechanism, of a pin tumbler lock having a key 20 plug, said key plug provided with a keyway, a rollback for operating said lock mechanism connected with the rear end of the key plug, a plurality of keys insertible into said keyway, a member on said pin tumbler lock 25 movable relative to said first rollback by only one of said keys, and a second rollback carried by said member and adapted to actuate said lock mechanism by means of said last named key; substantially as described.

13. The combination with lock mechanism, of a pin tumbler lock having a key 30 plug, said key plug provided with a keyway, a rollback connected to the rear end of the key plug and adapted to operate a 35 part of said lock mechanism, a plurality of keys insertible into said keyway, a spring-pressed member projecting into the keyway, and movable relative to the first rollback by engagement with one of said keys, and a 40 second rollback carried by said member and adapted to operate another part of said lock mechanism; substantially as described.

14. The combination with a mortise lock 45 having a case and two separate parts or members therein, of a pin tumbler lock having a key plug, said key plug provided with a keyway, a rollback connected with the rear end of the key plug, and adapted to operate one part or member of said mortise lock, a 50 second rollback adapted to operate another part or member of said mortise lock, a plurality of keys insertible into said keyway, and a movable member on said pin tumbler lock carrying said second rollback 55 and shiftable relative to the first rollback by one of said keys only and adapted when so shifted to operate the second named part or member of said mortise lock by means of said second rollback; substantially as described.

15. In a lock, the combination of a bolt- 60 mechanism having two tumblers, of a pin tumbler lock having a key plug, said key plug provided with a keyway, a rollback

connected with the rear end of the key plug 65 and adapted to operate one of said tumblers, a plurality of keys insertible into said keyway and adapted to operate said first rollback and a rollback on said pin tumbler lock movable relative to said first rollback 70 and actuated by one of said keys only to operate the other tumbler; substantially as described.

16. In a lock, a case, a sliding member therein, a primary tumbler for said sliding 75 member, having a rearwardly projecting lug, a secondary tumbler slidable on the case wall, back of said sliding member, and having a notched slot coöoperating with the lug of said primary tumbler, means for guiding 80 said secondary tumbler for forward and rearward movement, means for locking said secondary tumbler in its advanced and retracted positions respectively, and means for operating said tumblers; substantially as 85 described.

17. In a lock, the combination, with a bolt mechanism having two tumblers, of a pin tumbler lock having a key plug, said key plug provided with a keyway, a rollback 90 operative by said key plug and adapted to actuate one of said tumblers, a second rollback adapted to actuate the other tumbler, a plurality of keys insertible into said keyway for operating said first rollback, and a 95 member mounting said second rollback on said pin tumbler lock and movable relative to the first rollback by one of said keys; substantially as described.

18. A cylinder lock having two rollbacks, 100 and two keys for said lock, one of said rollbacks being movable rearwardly of said cylinder lock by the insertion of one of said keys, without being so moved by the insertion of the other key, in combination with 105 lock mechanism having a part to coöperate with said rearwardly movable rollback, when the latter has been moved rearwardly, and another part to coöperate with the other rollback; substantially as described. 110

19. In a lock, a latch bolt, a sliding member, a tumbler for said sliding member, means for retracting the latch bolt, and means operated by said tumbler to dog said retracting means; substantially as described. 115

20. In a lock, a latch bolt, a sliding member, a tumbler for said sliding member, means for retracting the latch bolt, and a lever operated by said tumbler to dog said retracting means; substantially as described. 120

21. In a lock, a dead bolt, primary and secondary tumblers therefor, means for operating said tumblers, a latch bolt, a latch bolt retracting device, and dogging means for said retracting device actuated directly 125 by said secondary tumbler; substantially as described.

22. In a lock, a dead bolt, pivoted tum-

blers therefor, a latch bolt, a knob shoe for retracting said latch bolt, and a dogging member for said knob shoe actuated directly by one of said tumblers; substantially as described.

5. 23. In a lock, a dead bolt, primary and secondary tumblers therefor, a latch bolt, a knob shoe for retracting said latch bolt, and a dogging lever for said knob shoe directly

operable by the secondary tumbler; substantially as described.

In witness whereof, I have hereunto set my hand on the 26th day of November, 1913.

WILLIAM E. SPARKS.
